UNITED STATES PATENT OFFICE.

MICHAEL PARIDON, OF BARBERTON, OHIO, ASSIGNEE TO THE DIAMOND MATCH COMPANY, OF CHICAGO, ILLINOIS, A CORPORATION OF ILLINOIS.

MECHANISM FOR DIPPING MATCH SPLINTS.

Application filed November 14, 1924. Serial No. 749,817.

This invention relates to splint dipping mechanism for match making machines, and more especially to mechanism for immersing progressing rows of splints in a solution of material which is adapted to prevent the after-glow of the splints when, as complete matches, they are individually ignited and the flame is extinguished.

The invention is particularly, though not exclusively, designed for use in connection with a match making machine having a continuously moving splint carrier which supports the splints in spaced parallel rows and transports them through the match making cycle, including an impregnating bath.

An object of my invention is to effect the immersion of the continuously travelling splints in the solution for a sufficient period of time to ensure the thorough impregnation of the splints with the solution.

Another object of the invention is to flex the carrier at the impregnating station in such a way as to permit the free and unobstructed passage of the walls of the solution-containing vessel between adjacent rows of splints.

Another object of the invention is to accomplish the relatively slow separation of the splints and the solution in which they are immersed, so as to obviate all liability of the formation and retention of globules of liquid on the free extremities of the splints and this without retarding the speed of the carrier.

With these and other objects in view, my invention comprises novel principles, features of construction, and combinations of parts, all of which will be hereinafter described and claimed.

In the drawings—

Figure 1 is a side elevation, partly in section, of splint impregnating mechanism embodying the principle of my invention, only so much of the match machine being shown as is necessary to illustrate the invention.

Fig. 2 is a detached perspective view of the reservoir for supplying liquid to the vessel.

Fig. 3 is a longitudinal vertical section through the vessel and its connections, showing the elements in their cooperative relation when the vessel is at its limit of descent.

Fig. 4 is a similar view, showing the ele-

ments in their relative positions when the vessel is at the limit of its ascent.

Fig. 5 is a section, enlarged through the vessel and a portion of the splint carrier with its projecting splints, showing the vessel as in its upward travel and the angular relation of the hinged carrier plates thereto in order to spread the rows of splints to permit the unobstructed upper passage of the walls of the vessel.

Fig. 6 is a similar section, showing the vessel fully elevated and the opposing tilted carrier plates straightened thereby.

Fig. 7 is a transverse vertical section through the splint carrier on a plane forward of the impregnating mechanism, as on the line 7—7 of Fig. 1.

Fig. 8 is a partial horizontal section on a plane above the vessel, as on the line 8—8 of Fig. 1.

Fig. 9 is a transverse section, partly in elevation, through the splint carrier, the vessel, and adjuncts.

Fig. 10 is a perspective of a portion of one of the carrier plates and a part of the adjacent rail on which the plate is supported and guided.

Fig. 11 is a similar view of the vessel, and adjuncts.

Fig. 12 is a like view of the vessel supporting bed and its link connections.

Referring to the drawings, 15 designates a portion of a continuously moving carrier by means of which rows of match splints are held in spaced parallel relation and are thus transported through the match-making cycle, including a vessel 16 containing impregnating liquid, such as a solution of ammonium phosphate, in which the travelling depending splints (17) on a horizontal run of the carrier are submerged. The form 95 of carrier herein illustrated comprises an endless chain of perforated plates having along their outer ends gear racks 18 with which mesh the teeth of actuating gear wheels in the usual manner. One of these 100 gear wheels is indicated at 19, Fig. 1.

The longitudinal edges of the horizontal run of the splint carrier travelling above the impregnating vessel, are supported and guided by parallel rails 20. Such rails have 105 ordinarily been constructed and arranged to deflect the carrier downward as it progressed to and above the vessel and then to raise the

carrier as it advanced to the rear of the vessel, thus dipping the depending splints into and raising them from the impregnating solution. Thereupon the impregnated splints 5 passed to and through a dryer, and thence to parafin-applying and other instrumentalities.

According to my invention the vessel containing the impregnating solution is given 10 a compound motion during the continuous travel of the splint carrier, that is to say, the vessel is rapidly raised toward the carrier so as to immerse the depending splints in the solution; it is then advanced concurrently with the carrier and, at the same time, 15 is gradually lowered to a plane below the splints, and it is then returned to its original position preparatory to a succeeding upward movement, and so on. The peculiar compound motion thus imparted to the vessel 20 ensures an effective dipping of the splints, the slow sinking movement preventing the retention of globules of liquid on the free extremities of the splints when the contents 25 of the vessel escape the splints, as will hereinafter appear.

In the present instance the vessel 16 is a 30 rectangular pan substantially the length of a match plate and the width of two hinged plates. Such pan is supported beneath the carrier in any suitable way to permit the requisite compound motion of the pan.

The supporting means herein illustrated 35 comprises a bed 21 mounted beneath the horizontal path of the carrier and its splints in such manner as to have capacity for reciprocation longitudinally of the carrier. In the present instance the bed rests on the bottom of a suitable drip pan 22 and is provided at its ends with standards 23 that 40 slidably embrace the overlying guide rails respectively. The standards 23 are connected by links 24 to a pair of depending arms 25, respectively, fast on a shaft 26 having 45 its bearings in brackets 27 on the supporting framework 28 of the match machine. Fixed on the shaft 26 is a rocker-arm 29 having a roll 30 which, by the action of a retracting spring 300 connecting the arm to an overhanging support 301 on the main frame, is 50 maintained in operative contact with a cam 31 carried by a shaft 32 which has its bearings in brackets 34 also mounted on the framework. The shaft 32 is continuously 55 driven from a suitable source of power, and to that end it is shown as equipped with a sprocket wheel 35 to which motion may be transmitted by a chain 36. The contour of the cam 31 is such that the arm 29 is lowered and permitted to rise during the 60 rotation of a cam, and the arms 25, in consequence, are oscillated to effect the reciprocation of the bed longitudinally of the carrier, the speed of the forward stroke of the bed 65 corresponding with that of the overlying

portion of the carrier, and the backward stroke being timed to return the bed to its original position and beneath the next succeeding portion of the carrier.

The standards 23 are provided with vertical guide ways 37 in which are slidably fitted up-projecting bars 38 to and between which guide blocks 39 on the respective ends of the pan are secured. These guide blocks are slidably fitted in the open sides of the 70 guide ways. The upper ends of the bars 38 are connected by suspension links 40 to rocker-arms 41 fast on a shaft 42 having its 75 bearings in brackets 43 on the supporting framework. Fixed to the shaft 42 is an arm 44 having a roll 45 that bears on a cam 46 carried by the driven shaft 32. The contour of the cam 46 is such that in an interval of its rotation the arm 44 is at rest; in another interval the arm is rapidly raised, and in another interval the arm is permitted to descend slowly until the position of rest is reached preparatory to a succeeding operating cycle. The described motions of the arm 44 are transmitted through the shaft 42, 80 rocker arms 41 and link connections to the pan 16, the latter in its upward motion encasing the depending splints on two overlying carrier plates and thus submerging such 85 splints in the contents of the pan, as previously explained.

During the relatively slow descent of the pan 16 it is carried by the bed 21 in the same general direction and at the same speed as the splint carrier until the open top of the pan clears the lower extremities of the splints, whereupon the pan is horizontally retracted by the bed to its original position below the splints and in readiness for a repetition of the immersing operation in respect 90 to the splints depending from the next following pair of plates of the travelling carrier, and so on.

In order to permit the rapid elevation of the pan, without liability of its walls 100 striking the depending splints of the carrier, I provide simple and efficient means for flexing the hinged plates located above the pan, in a manner to spread or diverge the end rows of splints of adjacent pairs of plates. Accordingly the upper surfaces of the rails 20 are interrupted with corresponding series of angulated portions which act 105 to flex the plates at their joints as such plates pass to, over and beyond the pan, that is to say, the rails are formed with undulating cam surfaces 47 adjacent the respective ends of the pan, which surfaces effect an angular disposition of the hinged plates during their travel, whereby each succeeding pair of plates, when they are positioned directly above the pan, are oppositely and 110 downwardly inclined from their hinge connection, and the respective plates which are 115 hinged to the lower edges of such inclined 120 plates pass to, over and beyond the pan, that is to say, the rails are formed with undulating cam surfaces 47 adjacent the respective ends of the pan, which surfaces effect an angular disposition of the hinged plates during their travel, whereby each succeeding pair of plates, when they are positioned directly above the pan, are oppositely and 125 downwardly inclined from their hinge connection, and the respective plates which are 130 hinged to the lower edges of such inclined

plates are inclined upwardly therefrom to the normal level of the rails. (See Fig. 5.) Consequently the rows of splints at the lower ends of the arched pair of plates above the pan, and the end rows of splints in the adjacent inclined plates, are spread apart when the arched plates are positioned directly above the pan, and ample space is thus afforded for the upward passage of the walls 5 of the pan below the hinged junctures of the plates.

As a simple and efficient means to straighten each succeeding series of flexed carrier plates when the pan is raised, and 10 thus permit the uniform immersion of the depending splints in its contents, the pan is provided with a pair of spaced-apart transverse bars 48 having enlarged end portions 49 which are arranged to bear against 15 imperforate bottom portions of the opposing arched plates as the pan approaches the limit of its upward movement. Since no splints depend from the imperforate portions of the plates, not only is the vertical 20 travel of the bars unobstructed by splints but the continuous travel of the carrier is unaffected by the bars. In the present instance plural bars 48 are provided, but a single bar may be used if desired.

The pan 16 is supplied with impregnating liquid in any suitable manner. In the present instance a reservoir 50 for the liquid is suitably supported in proximity to one end of the pan and has in its bottom an outlet 30 51 in vertical alignment with the mouth of an inlet fitting 52 in the end of the pan. The reservoir is provided with a depending member 53 which is fixed to an extended portion of the adjacent link 24, said reservoir thus being at all times positioned to supply 35 the impregnating liquid to the pan.

The bed 21 is preferably provided at its respective ends with up-standing lugs 54 which are so positioned as to embrace the 40 ends of the pan 16 and guide the latter in its vertical movement on the bed.

From the foregoing it will be seen that the peculiar compound movement of the pan in relation to the continuously moving splint 50 carrier ensures the immersion of the splints in the impregnating solution for a sufficient period of time to effect the thorough impregnation of the splints, and this without interfering with the normal speed of the carrier; 55 that the flexing of the carrier at the impregnating station permits the rapid and free entry of the walls of the pan between the rows of splints, without the otherwise necessity of re-spacing the splints on the carrier; and that the relatively slow removal 60 of the contents of the pan away from the splints obviates all liability of the formation and retention of globules of liquid on the free extremities of the splints. The formation 65 of such globules on the splint ends

would be objectionable, since their dissipation in the drying station of the match machine, preparatory to the paraffining operation, would require a prolonged drying interval in the presence of a high degree of 70 heat. This objection is effectually overcome by the step of slowly separating the splints and the impregnating bath as previously explained.

It is to be understood that my invention is 75 not limited to the particular construction herein disclosed as the mechanism may be modified within the principle of the invention and the scope of the appended claims.

I claim—

1. The combination with a splint carrier, of a vessel adapted to contain material for impregnating the splints, and means for producing a relative movement between said vessel and carrier to effect the immersion of 80 the splints in and their separation from the contents of the vessel, the motion of immersion being rapid and the motion of separation being relatively slow.

2. The combination with a splint carrier 90 of a vessel adapted to contain material for impregnating the splints, and means for moving said vessel toward and from the path of the splints in the carrier so as to immerse the splints in the contents of the vessel, said means being constructed to effect a rapid motion of the vessel toward the path of the splints and a relatively slow motion of the vessel away from such path.

3. The combination with a continuously 100 moving splint carrier, of a vessel adapted to contain material for impregnating the splints, and means for moving said vessel toward and from the path of the splints in the carrier and in the direction of movement of the carrier and back again, said means being constructed to effect a rapid motion of the vessel toward the path of the splints and a relatively slow motion of the vessel away from such path.

4. The combination with a splint carrier comprising a chain of flexibly connected plates, of a vessel adapted to contain material for impregnating the splints, means for moving said vessel toward and from the 115 path of the splints in the carrier so as to immerse the splints in the contents of the vessel, means for flexing the carrier plates directly above the vessel so as to incline said plates in opposite directions to each other 120 and thus cant the rows of splints in said plates to afford and unobstructed passage for the walls of the vessel, and means whereby the inclined plates are returned to their normal path when the splints are immersed in the contents of the vessel.

5. The combination with a splint carrier comprising a chain of flexibly connected plates, of a vessel adapted to contain material for impregnating the splints, means for 130

moving said vessel toward and from the path of the splints in the carrier so as to immerse the splints in the contents of the vessel, means for flexing the carrier plates directly above the vessel so as to incline said plates in opposite directions and thus cant the rows of splints in said plates to afford an unobstructed passage for the wall of the vessel, and means whereby the inclined plates are returned to their normal path when the splints are immersed in the contents of the vessel, the last-named means including a member arranged on the vessel to impinge against the said inclined plates when the vessel is moved toward the carrier.

6. The combination with a splint carrier comprising a chain of flexibly connected plates, and rails for supporting and guiding said carrier, said rails having cam surfaces whereby adjacent plates are inclined relatively to each other at one part of their traverse, of a vessel adapted to contain material for impregnating the splints, said vessel being located beneath the inclined plates, means for moving said vessel toward and from the path of the splints in said plates, and means whereby the inclined plates are returned to their normal path when the vessel is raised.

7. The combination with a splint carrier comprising a chain of flexibly connected plates, and rails for supporting and guiding said carrier, said rails having cam surfaces whereby adjacent plates are inclined relatively to each other at one part of their traverse, of a vessel adapted to contain material for impregnating the splints, said vessel being located beneath the inclined plates, means for moving said vessel toward and from the path of the splints in said plates, and means whereby the inclined

plates are returned to their normal path when the vessel is raised, the last-named means including a member arranged on the vessel to impinge against the said inclined plates.

8. The combination with a continuously moving splint carrier, of a vessel beneath the same, rock-arms above the carrier, flexible connections between said arms and the vessel, cam mechanism for actuating said arms to effect a rising and falling motion of the vessel, a bed reciprocative below the carrier, a vertical slidable connection between said vessel and bed, other rock arms mounted above the carrier, connections between said latter arms and the bed, and cam mechanism for actuating said latter arms to effect longitudinal reciprocation of the bed in timed relation to the rising and falling motion of the vessel.

9. The combination with a continuously moving splint carrier, of a vessel beneath the same, rock-arms above the carrier, flexible connections between said arms and the vessel, cam mechanism for actuating said arms to effect a rising and falling motion of the vessel, a bed reciprocative below the carrier, a vertically slidable connection between said vessel and bed, other rock arms mounted above the carrier, connections between said latter arms and the bed, cam mechanism for actuating said latter arms to effect longitudinal reciprocation of the bed in timed relation to the rising and falling motion of the bed, a supply reservoir flexibly supported adjacent to said vessel, and means providing communication between the said reservoir and vessel.

Signed at Barberton, in the county of Summit and State of Ohio this 12th day of November, A. D. 1924.

MICHAEL PARIDON.
